UNITED STATES PATENT OFFICE.

ANTON FRANK BROTZ, OF KOHLER, WISCONSIN, ASSIGNOR TO KOHLER COMPANY, OF KOHLER, WISCONSIN, A CORPORATION OF WISCONSIN.

GENERATOR REGULATOR.

Application filed April 21, 1921. Serial No. 463,432.

To all whom it may concern:

Be it known that I, ANTON FRANK BROZ, a citizen of the United States, and resident of Kohler, in the county of Sheboygan and 5 State of Wisconsin, have invented new and useful Improvements in Generator Regulators, of which the following is a description, reference being had to the accompanying drawings, which are a part of this specification.

10 This invention relates to generator regulators, and a particular object in view is to provide for widely varying the speed of the generator to correspond with great variations in the load while maintaining the voltage approximately constant.

15 While the invention is not confined to any particular adaptation, it is especially applicable to internal combustion engine driven 20 farm lighting and power plants and serves to approximately proportion the fuel consumption to the actual load.

25 Instead of regulating the voltage by maintaining constant speed, as usual with shunt or compound wound generators, a series field winding is used to buck or oppose the shunt field winding and thereby weaken the field strength as the load increases, while an automatic means simultaneously opens the throttle 30 of the engine to increase its speed. The two influences are so related that they maintain the voltage approximately constant.

35 With the above and other objects in view the invention consists in the generator regulator as herein claimed and all equivalents.

Referring to the accompanying drawing in which like characters of reference indicate the same parts in different views:

40 Fig. 1 is a diagram of a generator regulator embodying this invention;

Fig. 2 is a similar view of a modification thereof; and

Fig. 3 is a detail view of the throttle 45 actuating solenoid employed therein.

In these drawings 10 indicates a generator driven by an internal combustion engine whose throttle valve 11 is controlled by a solenoid having coils connected with the generator windings as will be described. The generator as shown is of the shunt type and supplies the mains 12 containing lamps 13 or other translating devices. The shunt field winding 14 of the generator is opposed by 50 a bucking series field winding 15 which be-

comes stronger as the load on the mains increases and thereby opposes a greater influence to the shunt field to weaken the field strength. At the same time a series coil 16, also in the load circuit and strengthened 60 by the increasing load, opposes to a greater extent the influence of a shunt or voltage coil 17 to effect a further opening movement of the throttle valve 11 of the engine to increase the speed of the engine. 65

As an example of a solenoid adapted for this purpose there is shown in Fig. 3 a solenoid 18 including the voltage coil 17 of many turns of fine wire which may be either connected in series with the shunt field 14 as 70 shown in Fig. 1, or in parallel therewith as shown in Fig. 2, and the current or series coil 16 of few turns of large wire enclosed within an iron casing 19 having an iron head 20. The solenoid core 21 movable with- 75 in the brass core tube 22 is pivotally connected to the shorter arm of a bell crank lever 23 fulcrumed on a brass cap 24. The core is pressed upwardly by a coil spring 25 and is centrally positioned within the core 80 tube and permitted to sway with the movements of the bell crank by having brass cross pins 26 through it slidably bearing on the core tube.

A link 27 connects the longer arm of the 85 bell crank lever 23 with the arm of throttle 11 so that in the extreme upper position of the core, as when the generator is not operating and the coils are therefore not energized, the throttle is held in a partly closed 90 position *a*.

When the generator is started with a minimum load or no load condition on the service mains, the series coil 16 opposes the voltage coil 17 only slightly or not at all and the 95 core will be drawn to its extreme lowermost position against the pressure of spring 25 and will move the throttle to a position *c* practically closing the intake manifold of the engine, so that the engine operates at 100 a minimum speed under which the generator develops the line voltage. As the load is increased and the generator field is weakened, as before mentioned, the influence of the bucking current coil or series coil 16 be- 105 comes greater, tending to neutralize the influence of the voltage coil 17 and permitting the spring 25 to lift the core and move the throttle toward its open position *b*, thus increasing the supply of fuel to the engine to 110

increase its speed corresponding with the increase in the load.

The full open position *b* of the throttle 11 is attained under the condition of maximum 5 load and should for any reason the current strength be increased beyond this as upon the occurrence of an overload, the further movement of the throttle toward the *a* position resulting therefrom will tend to slow 10 down the engine. Also, with automatic starting control, the partially closed position *a* of the throttle for starting prevents the engine from racing before connecting the generator with the load, as is done when it 15 is started with the throttle in full open position.

The proportioning of the field windings of the generator and of the coils of the solenoid and of the throttle and its operating means 20 is made to compensate for a change in load by a change in speed without a material change in voltage developed by the generator. The weakening of the generator field by the bucking coil serves to facilitate the increasing 25 of the speed of the engine caused at the same time by the bucking influence of the series coil of the solenoid, and this bucking field winding exaggerates the speed variation characteristic of the generator for 30 constant voltage conditions so that the desired object is accomplished of materially reducing fuel consumption to correspond with a reduction of load.

What I claim as new and desire to secure 35 by Letters Patent is:

1. A generator having an armature and a shunt field, service mains connected across the armature, a series field in series with the service mains and opposed to the shunt field, 40 an engine having driving connection with the generator, and means dependent on the current flow through the service mains for moving the throttle of the engine from a partly closed position past the full open position to the closed position.

2. In a generating plant, an internal combustion engine driven generator having a shunt field, a series field forming a bucking current coil in series with the service mains and opposing the shunt field, and a solenoid 50 having a coil in series with the service mains and having its core connected with the throttle of the internal combustion engine for opening said throttle from its closed position past the open position to a partly closed 55 position as the load on the service mains increases.

3. In a generating plant, an internal combustion engine driven generator having a shunt field, a series field comprising a bucking current coil in series with the service mains and opposing the shunt field to weaken the field as the load on the service mains increases, a solenoid having its core connected with the throttle of the internal combustion engine, a voltage coil on the solenoid tending to move the throttle to its closed position, and a current coil on the solenoid in series with the service mains opposing the voltage coil for moving the throttle toward 70 and past its open position as the load on the service mains increases.

4. In a generating plant, a generator having a shunt field, a bucking series field opposed to the shunt field for reducing the field 75 strength as the load increases on the service mains, a throttle for the internal combustion engine having means for urging it to a partly closed position, a solenoid connected with the throttle, a voltage coil of the sole- 80 noid tending to move the throttle from said position past the full open position to a closed position, and a bucking series coil of the solenoid in series with the service mains 85 opposing the voltage coil to move the throttle toward the full open position as the load on the service mains increases.

In testimony whereof, I affix my signature.

ANTON FRANK BROTHZ.
